SMUT MILL.

Patented Nov. 14, 1835.

Edward P. FitzPatrick of Mount Morris N.Y. U.S.A.
Patented Nov. 14, 1835. — Sellers Patent.

The Republics referred to in these Letters Patent and making part of the same containing a description in the words of the said Edward P. FitzPatrick himself of his improvement in the Grist machine for clearing grain.

To all to whom these presents shall come. Be it known that Edward P. FitzPatrick of Mount Morris, in the County of Livingston and State of New York, has invented a new and useful improvement in the Grist machine, and that the following is a full and exact description of the construction and mode of operation thereof, as invented or improved by me. I would state that the difference of my principle consists in allowing a free passage for small (or other matter to be disengaged from the grain) that it may be driven through the surrounding case or cylinder in which encloses the beaters and thereby disposed of as fast as separated.

Also that I apply the beaters in a spiral form around the axis, and composed them of long rods or bars, having sharp or ragged edges, through or amongst which the grain is dashed and driven about as it descends these spirals the axis thereof being placed vertically and revolving rapidly. On constructing I suspend with the old curving cylinder made of a continued sheet without openings, and in place of it substitute one made of rods or bars placed longitudinally in the circumference at such a distance apart as to allow the offensive particles to be driven out between them by the circulation produced by the revolution of the beaters. These rods I secure at the proper distance by uniting them into cast iron circular bands or hoops formed with grooves in the edges at top and bottom as they would stand, to which I place the ends of the rods at such a distance apart as may be thought to answer the end and then secure them by pouring in molten lead or other suitable metal about in hardening retarding them. These bands may be separated as often as requisite and will stand on above the other in a vertical position, and then supported by a corresponding circular frame and uprights which is closed at the top and the bottom around the axis except by having a sufficient aperture in the former for the grain to be introduced and in the latter

for it to be discharged. This frame and bands will be beat made in two semi-cylinders by dividing them longitudinally in which condition they are to be again united by means of bolts and screws. This is intended to give an opportunity to come at the interior in case of accident or any need of repairing. The shaft is to pass through the centre of this cylinder and is to be furnished with cross arms at stated intervals, as many as may be requisite which are also to have attached to them a plate of metal filling up the plan of the diameter to within a few inches of the extremity of said arms, or sufficiently remote from them to allow of a passage of the grain through the space thus left. This arrangement presents as it were a number of chambers through which the grain must pass in its descent. Now these arms are to be connected by a spiral beat, or formed of long square rods or bars running round from the top to the shaft and through these arms at such intervals apart as to allow the grain to be driven through or between them which is effected by the rapid revolution of the beaters, for as the grain falls down the inclined planes thereof, it is dashed from one to the other through the bars toward the bottom of the chamber over which it again pours into the next & so on. The bars are made of square iron in order to produce sharp edges, and these are again roughened by cutting thereon jagged notches so as to give every opportunity for dislodging the grain and also the small fibres of perfection at the small end of the grain which effects a material improvement in the process of cleaning it. The shaft is supported at its bottom on a step beneath the bottom of the outside cylinder, and is set in motion by the usual application of power.

What I claim as my own invention and not previously known in any other hewn bed improvement, and for which I ask Letters, Patent is, first, the manner of construction of the outside cylinder according to the principles above laid down, in permitting the disengaged matter to escape during the operation of the beaters — Secondly, the manner of construction in the spiral beaters as they are intended to be made of square shafts and rough edges between which the grain is cleaned according to the principles of those already set forth, and generally such manner of construction as any competent mechanist will perceive to be the distinguishing characteristics of my machine from those already used. Finally, the spiral form of

letter & claim for this purpose (as different from those heretofore used) for the construction shown. In testimony that the above is a full description of the construction and mode of operation of my improvement, as invented by me & have hereunto set my hand this twenty three day of October in the year eighteen hundred and thirty five.
